United States Patent Office.

NATHAN W. BAKER, OF LYNN, MASSACHUSETTS.

Letters Patent No. 91,593, dated June 22, 1869.

IMPROVED TYING-UP AWL.

The Schedule referred to in these Letters Patent and making part of the same.

To whom it may concern:

Be it known that I, NATHAN W. BAKER, of Lynn, county of Essex, and State of Massachusetts, have invented an Improved Tying-Up Awl; and do hereby declare the following to be a full, clear, and exact description thereof, reference being had to the accompanying drawings, in which—

Figure 1 represents an awl having my improvements. Figure 2 represents another view, also showing improvements.

Figure 3 is a section on line *x y* of fig. 1.

My invention has reference more particularly to use by shoemakers in tying together shoes of a pair, but it may be conveniently employed for many other purposes.

My object is to produce an awl by which a cord or string may be inserted into or pushed through leather or cloth, at the same time with the awl, and, when the awl is withdrawn, leaving the string or cord.

The drawings and description more clearly explain the nature of my invention.

In the drawings—

A is an awl fixed in the handle B.

Near the point of the awl, and in one side, is recess *c*, extending from *c'* to *m*. The recess is open at *c'*, but is partially closed at *m*, by tongue *d* coming up before it.

From *m* grooves *e e* extend each side of a seeming continuance of tongue *d* a short distance up the awl.

Now, when it is desired to put a cord through a piece of material, the quarter of a shoe for instance, when the shoes are to be tied together as pairs are put up, double the cord over between tongue *d* and the main part of the awl, letting the cord come back along grooves *e e*, holding both ends of the cord in the same hand with the handle; then push the awl with the cord through, and as the back of recess *c* slants to the point at *c'*, when the awl is withdrawn, the cord remains.

This saves much time and perplexity to shoemakers in putting up pairs of shoes, as it is quite a task to pierce the shoe, and then undertake to insert the cord, often requiring a minute or two to "string" both shoes, a tedious method still adhered to even in our best-appointed factories.

My invention can be employed to great advantage for many other purposes.

What I claim as my invention, and desire to secure by Letters Patent, is—

The awl A, having recess *c* scarfed, at *i*, substantially as set forth.

In testimony whereof, I have signed my name to this specification, in the presence of two subscribing witnesses.

NATHAN W. BAKER.
